UNITED STATES PATENT OFFICE

90,825

DESIGN FOR A RADIANT HEATER

Fred W. Waterman, Jr., Johnstown, Pa., assignor
to Century Stove & Manufacturing Company,
Johnstown, Pa., a corporation of Pennsylvania

Application August 9, 1933. Serial No. 48,970

Term of patent 7 years

To all whom it may concern:

Be it known that I, FRED W. WATERMAN, JR., a citizen of the United States, and resident of the city of Johnstown, county of Cambria, State of Pennsylvania, have invented a new, original, and ornamental Design for a Radiant Heater, of which the following is a specification, reference being had to the accompanying drawing forming a part thereof, and in which:

Figure 1 is a side view of a radiant heater in accordance with the present design; and Figure 2 is a perspective view thereof.

I claim:
The ornamental design for a radiant heater substantially as shown.

FRED W. WATERMAN, JR.
